US0D1108253S

(12) **United States Design Patent** (10) **Patent No.:** **US D1,108,253 S**
(45) **Date of Patent:** **** Jan. 6, 2026**

(54) **CONTAINER**

(71) Applicant: **All Plastic, Inc.**, Rancho Cordova, CA (US)

(72) Inventors: **William Thomas Smith**, Fair Oaks, CA (US); **Cheryl Ann Smith**, Fair Oaks, CA (US)

(73) Assignee: **All Plastic, Inc.**, Rancho Cordova, CA (US)

(**) Term: **15 Years**

(21) Appl. No.: **29/954,385**

(22) Filed: **Jul. 26, 2024**

Related U.S. Application Data

(63) Continuation-in-part of application No. 18/502,643, filed on Nov. 6, 2023, now Pat. No. 12,202,645, which is a continuation of application No. 17/989,464, filed on Nov. 17, 2022, now Pat. No. 11,905,069, which is a continuation of application No. 17/552,992, filed on Dec. 16, 2021, now Pat. No. 11,655,074, which is a continuation of application No. 16/874,394, filed on May 14, 2020, now Pat. No. 11,235,909, which is a continuation-in-part of application No. 29/691,120, filed on May 14, 2019, now Pat. No. Des. 945,877.

(57) **CLAIM**

The ornamental design for a container, as shown and described.

DESCRIPTION

FIG. 1 is a perspective view of a container; FIG. 2 is a right side view of the container shown in FIG. 1; FIG. 3 is a left side view of the container shown in FIG. 1; FIG. 4 is a front view of the container shown in FIG. 1; FIG. 5 is a rear view of the container shown in FIG. 1; FIG. 6 is a top plan view of the container shown in FIG. 1; and, FIG. 7 is a bottom plan view of the container shown in FIG. 1.

The broken lines shown in the Figures represent portions of the container that are unclaimed and form no part of the claimed design.

1 Claim, 4 Drawing Sheets
